2,678,402

ACCELERATION CONTROL DEVICE FOR
ENGINE-GENERATOR SETS

Arthur L. Altemose, Williamsport, Pa., assignor
to Avco Manufacturing Corporation, Cincinnati, Ohio, a corporation of Delaware

Application June 7, 1951, Serial No. 230,407

7 Claims. (Cl. 290—40)

1

The present invention relates to a control mechanism for regulating the power output of an engine driving energy producing means, such as a plurality of electrical generators. More specifically, this invention concerns a combination of electrical and mechanical elements which are adapted to control the rate of loading of an engine generator set.

For many years portable engine generator sets have been used for supplying electrical energy to auxiliaries and are coming into wide spread use for starting jet aircraft engines.

In such engine generator sets, it is commonplace to provide generator capacity having a maximum output which is substantially equal to the rated full load output of the engine which may be an internal combustion engine, such as an Otto engine. In these sets, it is important that the engine be loaded at a rate that permits the engine to accelerate to its maximum rated speed at which full power output can be developed. Should the load be applied at an excessive rate, stalling may occur which is obviously highly undesirable, particularly when a jet engine must be started which is urgently needed for military purposes.

The present invention comprises an extremely simple, effective control mechanism that prevents improper loading of an engine generator set and makes it possible to impose a very large load instantaneously on the generators without stalling the engine driving the generators. The mechanism of the present invention temporarily breaks the circuit of one of the generators and permits rapid acceleration of the engine until full operating speed is attained at which time the generator circuit is reestablished so that the generator can assume its proportionate share of the load. Such a method of operation not only prevents stalling and permits very rapid acceleration of the engine but also insures that the full generator load will only be imposed on the engine when it is operating at a speed at which sufficient power can be developed.

Briefly stated, the present invention comprehends the provision of an electrical switch in the control circuit of one of a plurality of generators driven by the engine. This switch is cooperatively positioned relative to a speed regulating governor driven by the engine. The governor regulates the throttle valve position of a charge forming means or other fuel flow regulating device for the engine. The switch is actuated by the governor when it opens the throttle valve to an extreme wide open position beyond the

2

position assumed by the throttle during ordinary operation, even at full load. When thus actuated, the switch temporarily breaks the control circuit of one of the generators, rendering it ineffective for generating electrical energy. Thus partially relieved of its load, the engine can rapidly accelerate in speed. When full speed has been attained, the governor moves to close the throttle valve and the switch is disengaged. 10 As a result the control circuit of the generator is again completed making it possible for the generator to assume part of the load and for equilibrium to be established with the engine developing full power output at maximum rated speed.

The present invention is particularly useful in conjunction with an engine generator set although it should be appreciated that it can also be used to advantage for controlling other installations where an engine drives a power consuming element, such as a pump. The present invention can be adapted for use in such installations through the provision of an electrical circuit controlling the output of the pump or comparable element.

In view of the foregoing, it is an important object of the present invention to provide means for controlling the rate of loading of an engine in an engine generator set so that stalling of the engine, as it is loaded, is prevented.

A further object of the invention is the provision of an electrical control mechanism actuated by an engine governor whereby the loading of an engine generator set is controlled so that stalling is prevented and rapid acceleration is permitted.

Another important object of the present invention is to provide a control mechanism for an engine generator set that prevents overloading of the set.

More specifically, it is an object of the present invention to provide a control switch in the control circuit of one of a plurality of generators in an engine generator set, the switch being actuated by a multispeed governor as the governor moves the fuel regulating means of the engine to its extreme wide open position, actuation of the switch temporarily rendering ineffective one of the generators for producing electrical energy.

The novel features that are considered characteristic of the invention are set forth in the appended claims; the invention itself, however, both as to its organization and method of operation, together with additional objects and advantages thereof, will best be understood from

the following description of a preferred embodiment when read in conjunction with the accompanying drawings, in which:

Figure 1 is a side elevational view of a complete portable engine generator set, the access doors of the set being shown in their open positions to facilitate illustration of the interior construction of the set;

Figure 2 is an elevational view to an enlarged scale of the carburetor of the engine in conjunction with a multispeed governor and an electrical switch associated with the electrical circuit of one of the generators of the engine generator set; and

Figure 3 is a schematic wiring diagram showing the electrical control circuit of a pair of generators included in the engine generator set.

The mechanism of the present invention is particularly useful for controlling the rate of loading of an engine generator set, generally designated 1, illustrated in its entirety in Figure 1. Engine generator sets of this type may include ground wheels 2 to permit transportation around airfields where the set may be used to start aircraft engines.

The set includes a chassis 3 on which body 4 is mounted, the body including access doors 5 and 6 which have been shown in their open positions to facilitate the illustration of the interior.

The set includes an engine 7 which drives generators, generally designated 8. A pair of generators has been shown for purposes of illustration, although it should be appreciated that more than two generators may be provided if desired. A fuel flow regulating device, or a charge forming device such as carburetor 9, is provided for engine 7.

Engine generator sets of the type illustrated may be used to supply electrical energy for the starter motors (not shown) associated with the aircraft engines to be started. Normally the set idles at a relatively low speed until such time that the starter motors are connected to generators 8. Imposition of this load on the generators causes the engine 7 to slow down and a governing mechanism, to be described more fully hereinafter, adjusts the throttle setting of carburetor 9 to increase the speed of engine 7 until full power output can be developed and the generators 8 are supplying desired current to the starter motors of the aircraft engine being started.

The mechanism of the present invention is shown in detail in Figure 2 in which carburetor 9 is fully illustrated. With reference to this figure, it will be noted that the carburetor includes a pair of throttle valves 10 and 11 in series. The particular carburetor illustrated is of the down draft type, air being aspirated through its upper end, the air picking up fuel during its passage through the carburetor to form a combustible mixture which is supplied to engine 7 through an intake manifold, a portion of which is indicated at 12. The quantity of fuel air mixture admitted to the engine is controlled by throttle valves 10 and 11 which are pivotally secured to transverse shafts 13 and 14, respectively.

The position of throttle valve 10 may be manually adjusted by means of an associated arm 15. This throttle valve is used when the engine is first started after which it is moved to a wide open position indicated in Figure 2 in which position it remains during the time that the engine is in operation and under governor control.

Throttle valve 11 is adjusted by means of arm 16 the position of which is controlled by a multispeed governor, generally designated 17. The governor is driven by the engine through splined shaft 18 and is driven at all times at a speed proportional to engine speed.

The governor may be of any conventional type suitable for the purpose but preferably should be of the fly-ball type which operates to maintain the associated engine at a constant speed of operation, this speed depending upon the governor setting. This setting is determined by the position of a bell-crank 19 which is pivotally attached to the governor as at 20. The position of bell-crank 19 determines the tension of spring 21 and, as will be described more fully hereinafter, pre-determines the governed speed at which the engine will be maintained.

Governor 17 imparts swinging movements to arm 22 about shaft 23. As the engine speed decreases from any pre-determined speed setting, the governor swings arm 22 counterclockwise thereby opening throttle valve 11 by means of interconnecting link 24. As the engine speed rises above the pre-determined speed setting, arm 22 is swung clockwise to close throttle valve 11 and reduce the operating speed of the engine.

The swinging movements of arm 22 are controlled in part by the tension of spring 21. Thus, as bell-crank 19 is rotated clockwise about pivot point 20, spring 21 is stretched and its tension is increased. Simultaneously, the increased tension of spring 21 tends to move arm 22 counterclockwise and open the throttle valve. Correspondingly, the engine speed increases until the forces developed within governor 17 are sufficient to overcome the increased tension load of spring 21. When this condition has been attained, arm 22 is moved clockwise and the engine generator set comes to equilibrium at a new operating condition, at a speed higher than that which prevailed prior to the time that bell-crank 19 was moved in a clockwise direction.

The specific mechanism for rotating the bell-crank constitutes no part of the present invention and has been described and claimed fully in Patent No. 2,622,576 entitled "Two Speed Engine Governor" issued to A. W. Rickenbach on December 23, 1952. For the purposes of the present invention, it is sufficient to understand that governor 17 with bell-crank 19 and spring 21 constitutes a multispeed governor which can be adjusted to establish pre-determined constant operating speeds at which the engine will be held under various load conditions.

Governor 17 per se may be a conventional fly-ball governor such as is commercially available.

Positioned immediately below governor 17 is an electrical switch 25 having projecting switch actuating arm 26 which is positioned for engagement by arm 22 in the course of its movement. Switch 25 is adjustably secured to bracket 27 which projects from and is rigidly secured to a fixed engine mounting plate 28. If desired, switch 25 can be located elsewhere on the governor or carburetor in position to be operated by arm 22 and the associated linkage.

With specific reference to Figure 2, it will be noted that actuating arm 26 is engaged by arm 22 when it is in its extreme counter-clockwise position at which time throttle valve 11 is held in its extreme wide open position. With reference to this same figure, it will be observed that arm 26 is disengaged by arm 22 when in its dash line position at which time throttle valve 11 is in a par-

stially open position, as indicated in phantom lines.

With reference to Figure 3, the control circuit for generators 8 is shown schematically. One of these generators is designated in the schematic diagram as generator I whereas the other generator is indicated as generator II. These generators generate electric current which is supplied through relays 29 and 30 to a load, indicated at 31, which may be the starter motor of an aircraft engine to be started.

A manual control switch 32 is connected in series with a battery or other source of low potential 33, one side of the battery being grounded as at 34, the other side being connected to switch 32. When manual control switch 32 is closed, current flows from battery 33 through coils 35 and 36 of relays 29 and 30, respectively. Energization of these coils closes switches 37 and 38 of relays 29 and 30 thereby completing the circuit from generators I and II, respectively, through load 31 to ground.

Switch 25 is connected in series between coil 36 and manual switch 32. Switch 25 is normally closed to complete the circuit through holding coil 36 when switch 32 is closed. When arm 26 of switch 25 is engaged by governor arm 22, it is forced open, that is, contact member 39 is moved from the phantom line to the full line position as illustrated in Figure 3. When thus held open by governor arm 22, switch 25 breaks the circuit of generator II and the generator is rendered ineffective for producing electrical energy for load 31.

When governor arm 22 moves out of engagement with switch 25, contact member 39 returns to its closed position again completing the circuit through coil 36 and restoring the connection between generator II and load 31. It is to be noted that generator I remains connected to load 31 under all conditions of operation, so long as manual switch 32 remains in its closed position.

Frequently engine generator sets of the type herein described must stand ready for immediate use for long periods of time. At such times engine 7 is kept in operation. It is desirable that the engine idle at a fairly low speed and accordingly bell-crank 19 is adjusted to relieve the tension of spring 21, thus permitting governor arm 22 to move away from switch 25 and permitting throttle valve 11 to remain in a relatively closed position. At such times engine 7 idles at a speed of about 1300 R. P. M.

When an aircraft engine is to be started, a starter motor, which comprises load 31, is connected in circuit with generators I and II and manual switch 32 is closed to impose the load of the starter motor on the generators. This sudden application of load instantly tends to reduce the speed of engine 7. As soon as this reduction in speed occurs, bell-crank 19 is rotated clockwise, tensioning spring 21 and swinging governor arm 22 counterclockwise. Such movement of the governor arm immediately opens throttle valve 11 to its extreme wide open position and simultaneously forces switch 25 open. Opening of switch 25 disconnects generator II from load 31 and temporarily reduces the load imposed on the engine 7. This reduction of load simultaneous with the opening of throttle valve 11 permits engine 7 to accelerate rapidly.

As soon as the engine has accelerated to full speed, about 2200 R. P. M., governor 17 acts to swing governor arm 22 clockwise in opposition to spring 21, simultaneously partially closing throt-

tle valve 11 and permitting switch 25 to close, re-establishing the circuit between generator II and load 31. The imposition of the full load of both generators on engine 7 after the engine is operating at full speed enables the engine to assume the full load without stalling.

Were it not for the present invention, the sudden imposition of the full load on engine 7 while it is idling at 1300 R. P. M. would cause the engine to stall since the load would be too great to permit acceleration. One way of solving this problem, aside from the present invention, would be to provide an oversized engine 7 which would be capable of accelerating even under full load conditions. However, this does not offer a practical solution since it is desirable, for reasons of cost and weight, to use the smallest engine possible.

It is to be noted that governor arm 22 does not engage switch 25 until throttle valve 11 is in its extreme full open position. Thus, governor 17 may regulate the position of throttle valve 11 over a large operating range without actuation of switch 25. In other words, under full speed full load conditions, governor 17 holds throttle valve 11 in a position slightly less than full open. It is only when the engine is overloaded that the governor opens the throttle valve still further in an attempt to maintain engine speed that arm 22 engages switch 25. Thus the mechanism of the present invention is also effective for preventing overloading of the engine generator set, for when such overloading does occur, switch 25 is engaged and a part of the load, in other words a part of the generator capacity, is cut out. When partially relieved of load, the engine can reattain its full speed, after which full load is again imposed on the engine as has been explained. If the overload condition is continued, the set will cycle between partial and full generating capacity and stalling will be prevented. Cycling will continue until the overload is removed.

It will be appreciated by those skilled in the art that the present device is very beneficial, particularly when applied to engine generator sets which must be held in readiness for instant use for starting military aircraft. It is to be observed that the present invention, although very simple, is foolproof and effective for preventing overloading and stalling of an engine generator set.

When load 31 is removed from the system, as for instance, when the aircraft engine has been started, switch 32 is opened and bell-crank 19 is swung counterclockwise to relieve the tension of spring 21. Under such conditions governor 17 immediately moves arm 22 clockwise closing throttle valve 11 and re-establishing idling conditions at about 1300 R. P. M.

Having described a preferred embodiment of my invention, I claim:

1. In combination with an engine generator set having a plurality of generators driven by an engine, a fuel control means for the engine having a movable member for regulating the flow of fuel to the engine, a governor driven at a speed proportional to engine speed, said governor adjusting the position of the movable member of said fuel control means to maintain a pre-determined speed-load relationship for the engine generator set, an electrical switch actuated by said governor when it moves the movable member to a position of maximum fuel flow, said switch being in circuit with one of the generators, actuation of said switch temporarily rendering the

associated generator ineffective for producing electrical energy.

2. In combination, an Otto engine, a pair of electrical generators driven by said engine, a carburetor for supplying combustible mixture to said engine, an adjustable throttle valve in said carburetor, a governor driven by said engine, said governor being connected to said throttle valve to adjust its position to maintain a pre-determined speed-load relationship for said engine, an electrical switch in circuit with one of the generators, said switch being actuated by said governor when said governor moves said throttle valve to its extreme open position, actuation of said switch temporarily rendering the associated generator incapable of generating electrical energy.

3. In combination in an engine generator set of the type including an internal combustion engine in driving relationship with a plurality of electrical generators which are connected in circuit to deliver electrical energy to a common load, a carburetor for supplying a combustible mixture to the engine, an adjustable throttle valve in said carburetor, a multi-speed governor for adjusting the position of said throttle valve to hold the engine speed to pre-determined constant values, and an electrical switch in circuit with one of the generators, said switch being actuated by said governor when said governor moves said throttle valve to its extreme open position, actuation of said switch temporarily breaking the circuit of one of the generators whereby it is rendered incapable of delivering electrical energy to the load.

4. In combination with an internal combustion engine and a plurality of electrical generators driven by the engine, a carburetor for supplying a combustible mixture to the engine, an adjustable throttle valve in said carburetor, a multi-speed governor for adjusting said throttle valve to pre-determined positions to hold engine speed at pre-determined constant values, and an electrical switch actuated by said governor when said throttle valve is opened to its extreme position, actuation of said switch breaking the electrical circuit of one of the generators whereby it is temporarily rendered ineffective for generating current.

5. In combination with an engine and a plu- 50

rality of electrical generators driven by the engine, a charge forming means for the engine, an adjustable throttle valve in said charge forming means, an engine driven governor for adjusting said throttle valve to maintain a pre-determined speed-load relationship for the engine, and an electrical switch actuated by said governor when said throttle valve is opened by said governor to its extreme position, actuation of said switch breaking the electrical circuit of one of the generators.

6. In combination with an engine and a plurality of electrically controlled loading means driven by the engine, a charge forming means for the engine, an adjustable throttle valve in said charge forming means, a governor for adjusting said throttle valve to maintain a pre-determined speed-load relationship for the engine and an electrical control element in circuit with certain of the plurality of loading means, said control element being actuated by said governor to remove the load of one or more of said loading means when said throttle valve is opened by said governor to its extreme position.

7. In combination with an internal combustion engine and a plurality of loading means driven by the engine, a charge forming means for the engine, an adjustable valve in said charge forming means regulating its output to the engine, valve control linkage for adjusting the position of said valve, and an element controlling the load of certain of said plurality of loading means, said last named element being actuated by said valve control linkage to remove the load of one or more of said loading means controlled by said element when said valve is opened by said linkage to its extreme position.
